UNITED STATES PATENT OFFICE.

ARTHUR F. REINHEIMER, OF DETROIT, MICHIGAN.

POOL-CUE-TIP HOLDER.

1,390,722.

Specification of Letters Patent. Patented Sept. 13, 1921.

Application filed January 6, 1921. Serial No. 435,449.

To all whom it may concern:

Be it known that I, ARTHUR F. REINHEIMER, a citizen of the United States, residing at Detroit, in the county of Wayne 5 and State of Michigan, have invented certain new and useful Improvements in Pool-Cue-Tip Holders, of which the following is a specification.

This invention relates to fastenings for 10 the tips of cues used in pool and billiards, and the primary object of the invention is to provide an improved means for positively holding a cue tip in position, whereby the accidental displacement thereof will be 15 eliminated.

Another object of the invention is to provide a cue tip fastener which permits the placing and removing of a tip on a cue in a convenient, easy and expeditious manner, 20 and which will eliminate the time and labor consuming methods now in vogue.

A further object of the invention is to provide an improved device for holding a pool cue tip in position, which is durable and 25 efficient in use, one that is simple and easy to manufacture, and one which can be placed upon the market and associated with the ordinary types of cues at a reasonable cost.

With these and other objects in view, the 30 invention consists in the novel construction, arrangement and formation of parts as will be hereinafter more specifically described, claimed and illustrated in the accompanying drawings, forming a part of this specification, in which:

Figure 1 is a side elevation of an upper 35 end of a cue showing the improved invention applied thereto.

Fig. 2 is a longitudinal fragmentary section through the upper end of a cue and 40 the improved cue tip holder.

Fig. 3 is a view similar to Fig. 2 showing 45 the cue tip clamping jaws in their inoperative extended position ready to receive a tip therebetween.

Fig. 4 is a detail diametric section taken on the line 4—4 of Fig. 2, and

Fig. 5 is an enlarged side elevation of 50 the member carrying the jaws for engaging the cue tip.

Referring to the drawings in detail, 55 wherein similar reference characters designate like and corresponding parts throughout the several views, the letter A indicates a cue and B, the improved holder for the cue tip C. The cue A may be of the usual

or any preferred type, weight or length and includes the gradually tapered body 10, which has the outer end thereof provided with the reduced cylindrical extension 11, 60 which forms the circumferentially extending shoulder 12.

The tip C which is adapted to be held in position on the cue A by means of the improved holder or fastener B includes a cylindrical body 14 having its outer surface convex as at 15, as in the usual construction of cue tips. The inner end of the tip body 14 is provided with a reduced extension 16 and the body intermediate its ends in advance of the reduced portion 16 is provided with inwardly extending arcuate substantially semi-circular grooves 17, the purpose of which will be hereinafter more fully described. 75

The improved holder B includes a ferrule 18 which is fitted upon the reduced cylindrical extension 11 of the body 10 of the cue A, and this ferrule is placed in abutting engagement with the annular circumferentially extending shoulder 12. The ferrule 18 may be held in place by any desired means, either by friction, a suitable adhesive, or by suitable fastening elements. The outer end of the ferrule is provided with a reduced extension 20 upon which is adapted to rotatably fit the tubular housing 21. The tubular housing 21 projects outwardly beyond the outer end of the cue A. Arranged axially within the housing 21 is a screw 22, the inner end of which is provided with relatively coarse threads 24 for engagement with the cue body 10, and is threaded axially into the same. The outer portion of the screw 22 is provided with machine threads 25, upon which a traveling nut 26 is threaded. The extreme outer end of the screw 22 is provided with a head 27, which may, if so desired, be provided with the usual bit receiving slot 28'. 100

A sleeve 28 is rotatably mounted within the housing 21, and suitable pins 29 are utilized for rigidly connecting the traveling nut 26 with the inner end of the sleeve 28. Thus it can be seen that when the nut 26 is moved longitudinally of the screw 22, the sleeve 28 will be moved therewith. If so desired the outer surface of the nut 26 adjacent to the outer end thereof may be rabbed for the reception of the inner end of the sleeve 28. The outer end of the sleeve 28 is provided with a pair of diametrically

opposed inwardly extending longitudinally disposed slots 30, which divide the outer end of the sleeve into a pair of gripping jaws 31 and 32. In order to facilitate the spreading of the jaws 31 and 32 in relation to each other, the inner end of each of the slots 30 is provided with diverging inwardly extending arcuate slots 33. Thus it can be seen that each of the jaws 31 and 32 are connected 10 to the main portion of the sleeve 28 merely by relatively small tongues 34. The outer ends of each of the jaws 31 and 32 are provided with outwardly extending arcuate flanges 35, which are adapted to engage the 15 outer surface of the housing 21, so as to limit the inward movement of the sleeve 28 into the housing. These flanges 35 are then bent back upon themselves inwardly toward the center of the sleeve to provide jaw faces 20 36, the inner surfaces of which are substantially semi-circular shaped. Between the semi-circular shaped jaws 36 the reduced portion 16 of the tip C is adapted to be placed, and the working faces 36 are adapted 25 to ride into the grooves 17 formed in the tip.

In assembling the holder B upon the cue end A, the ferrule 18 is placed upon the reduced cylindrical extension 11 of the body 10 of the cue and secured thereon against 30 movement, after which the housing 21 is mounted for rotary movement upon the reduced portion 20 of the ferrule 18 and is held against accidental displacement thereon by means of pressing in the annular rib 38, 35 into the groove 39 formed in the ferrule. After the housing has been placed in position the screw 22 is threaded into the nut 26, until the same assumes the position as shown in Fig. 3 of the drawings, after which 40 the wood screw portion 24 of the screw 22 is forced into the end of the cue body. The threading of the screw into the end of the cue body slightly expands the reduced portion 11 of the cue body 10, which further 45 tends to hold the ferrule on position. After the screw has been placed in position as shown in Fig. 3 of the drawings, the cue tip C is placed between the working faces 36, of the sleeve and the same are moved 50 into the grooves 17 by pressure exerted by the thumb and forefinger. The housing 21 is then held against rotary movement and the cue A is rotated, which will turn the screw 22 and thus thread the nut 26 down 55 upon the same. The sleeve 28 is held from accidental rotation by means of its frictional contact with the housing 21 and it is to be understood that a snug frictional contact is set up between the meeting surfaces 60 thereof. As the sleeve 28 is brought into the housing 21, the jaws 31 and 32 will be brought toward each other and the cue tip held securely in place against accidental movement.

65 When the cue tip is worn, it is merely nec-

essary to then hold the housing 21 against rotation, and rotate the cue A in a reverse direction for turning the screw 22, so that the nut 26 will be threaded toward the outer end of the same, which will move the jaws 70 31 and 32 out of the housing and thus permit the removal of the tip C.

From the foregoing description, it can be seen that an exceptionally simple and durable device has been provided for effectively 75 holding the cue tip against accidental displacement, and which will permit the easy and convenient removal or replacing thereof when so desired or necessary.

Changes in details may be made without 80 departing from the spirit or scope of this invention; but,

I claim:

1. In a mounting for cue tips, the combination with a cue and a tip therefor, of a 85 holder for the tip including a screw extending outwardly from the cue and non-rotatably secured thereto, a housing rotatably mounted upon the outer end of said cue and receiving said screw, a traveling non-rotatable nut mounted upon said screw, a sleeve 90 secured to said nut and frictionally engaging the inner surface of the housing, jaws carried by the sleeve and arranged to normally assume a position out of engagement with each other, inwardly extending arcuate working faces formed on the outer ends of the jaws, the jaws being adapted to be brought into engagement with each other when the sleeve is brought into the housing, the cue tip having arcuate inwardly extending grooves arranged to receive the working faces, whereby when the jaws are brought toward each other accidental displacement of the tip is eliminated. 100

2. In a mounting for cues, a ferrule circumscribing the outer end of a cue, a housing rotatably mounted upon the ferrule and projecting beyond the outer end thereof, a screw arranged axially within the housing 110 and non-rotatably carried by the outer end of the cue, a sleeve having a diameter substantially equal to the diameter of the housing arranged within the housing, a nut mounted upon the screw, means for securing the inner end of the sleeve to said nut, a pair of resilient jaws formed upon said sleeve and arranged to normally extend beyond the circumference of the housing, inwardly extending arcuate working faces formed on the jaws, and a cue tip having arcuate recesses arranged to receive the working faces. 115

3. The combination with a cue tip having a reduced outer end, of a device for holding a tip in position on the cue including a ferrule non-rotatably mounted upon the reduced end of the cue, a housing rotatably mounted upon said ferrule, and extending beyond the ferrule and cue, a machine screw 125 130

arranged axially in said housing and non-rotatably carried by said cue, a head formed on the outer end of said machine screw, the inner end of the screw having a cue engaging portion formed thereon, a cylindrical sleeve arranged to snugly fit within said housing, a nut threaded upon said machine screw, means for securing the nut to the inner end of said sleeve, outwardly extending flanges formed on the outer end of the sleeve arranged to engage the outer end of

the housing to limit the inward movement of the sleeve within the housing, the sleeve being provided with inwardly extending diametrically opposed longitudinally extending slots, inwardly extending arcuate working faces formed on the sleeve on each side of the slotted portion thereof, and a compressible cue tip having arcuate recesses formed in the opposite faces thereof adapted to receive said working jaw faces.

ARTHUR F. REINHEIMER.
